UNITED STATES PATENT OFFICE.

FRITZ ENGEL, OF WORMS, ON THE RHINE, AND CARL WAGNER, OF OFFENBACH, ON THE MAIN, GERMANY.

LEATHER-SKIVING MACHINE.

SPECIFICATION forming part of Letters Patent No. 367,709, dated August 2, 1887.

Application filed October 15, 1886. Serial No. 216,314. (No model.)

To all whom it may concern:

Be it known that we, FRITZ ENGEL, engineer, of Worms, on the Rhine, and CARL WAGNER, of Offenbach, on the Main, both in 5 the Empire of Germany, have invented new and useful Improvements in Leather Skiving, Paring, or Sharpening Machines, of which the following is a specification.

The object of our invention is to provide a 10 new and improved machine for skiving the edges of leather or for thinning other portions of the surface of a sheet of leather, and which is specially adapted for the use of saddlers, trunk-makers, book-binders, and others using 15 leather in manufacturing various articles.

The invention consists of various parts and 20 details and combinations of the same, as will be fully described hereinafter, and then pointed out in the claims.

Reference is to be had to the accompanying 25 drawings, forming a part of this specification, in which similar letters of reference indicate corresponding parts in both figures.

Figure 1 is a front elevation of our improvement, and Fig. 2 is a side elevation of the 30 same, parts being in section.

On the base or bed plate A is mounted a standard, B, of suitable construction and provided with a driving-wheel, C, rotated by 35 suitable means. The wheel or pulley C is used as a crank-disk, and connects by the rod D with the crank-arm E, secured on the oscillating shaft F, mounted in suitable bearings on the standard B and carrying on its front end 40 the crank-arm G, which operates the arm H, connected with the guide-arm I, sliding vertically in suitable bearings on the said standard B and provided with the knife J, adjustably secured to the said guide-arm I. The crank-

arm K is also secured to the said oscillating shaft F, and connects by the links L and L' with the levers M and M', respectively, of which the lever M' connects by the rod O with the bell-crank lever P, one arm, P', of which 45 operates on the pin Q', secured to the plate Q, sliding sidewise in the guide Q', formed on the standard B and carrying the vertical feed-bar R, having a lug or pin, R', in its front, on which operates the arm S' of the lever S, connected by the rod T with the lever M. A 50 spring-rod, U, operates against one edge of

the sliding plate Q, and a similar spring-rod, U', presses against the upper end of the feed-bar R, the foot R² of which is provided with teeth and rests directly above a table, R³. 55

A segmental support, V, is located below the feed-bar R in front of the knife J, and is mounted on the shaft V', having its bearing in the frame W, adapted to slide in the keeper A', attached to the bed-plate A. The frame 60 W is moved forward and backward by turning the hand-wheel W', secured to the shaft W², screwing in the frame W.

The shaft V' is provided with the segmental gear-wheel V², which meshes into the worm 65 V³, formed on the shaft V⁴, provided on its outer end with the hand-wheel V⁵.

The links O and T are adjusted at their 70 lower ends on their respective levers P and S.

The operation is as follows: The rotary motion of the pulley C imparts an oscillating motion to the shaft F, which oscillates the distance of one-quarter revolution. The movement of the shaft F imparts a vertical reciprocating movement to the knife J by means of the crank-arm G and the connecting-arm H. The shaft F also imparts a sidewise motion to the plate Q, carrying the feed-bar R, by means of the crank-arm K, acting on the lever M', which, by means of the link O, actuates the lever P, the arm P' of which operates on the pin Q' of the said plate Q. A vertical motion is imparted to the feed-bar R from the main shaft F by means of the crank-arm K, actuating the lever M, which, by means of the link T, imparts motion to the lever S, and the latter, by means of its arm S', acting on the pin R' of the feed-bar, raises the latter. The return movement of the plate Q is accomplished by the spring-rod U, and the downward motion 75 of the feed-bar R is accomplished by the spring-rod U'. The leather to be skived or thinned on its edges is placed upon the table R³, with the portion to be skived or thinned depending in front of and held against the 80 segmental support V, and the knife J, in descending, cuts the leather according to the position which the support V holds in relation to the knife J. This position of the support V is regulated by turning the wheels W' and V⁵, of which the former causes a forward and 85 backward motion of the said support and the 90

latter a revolving motion, by which the angle of presentation of the outer vertical face of the said support is varied to the plane of movement of the knife, according to the extent of the surface of the leather to be skived or thinned.

Having thus fully described our invention, we claim as new and desire to secure by Letters Patent—

- 10 1. The combination, with the vertically-reciprocating knife J, of the feed-bar R, the segmental support V, and means for imparting a forward and backward motion to the said support, substantially as shown and described.
- 15 2. The combination, with the knife J, adjustably secured to the vertical rod I, sliding in suitable bearings, of the arm H, connected with the said rod I, the crank-arm G, operating on the said arm H, the shaft F, carrying
- 20 the said crank-arm, the crank-arm E, secured to the said shaft F, the link D, attached by one end to the said crank-arm E, and the rotating pulley C, acting as a crank-disk for the said link D and imparting an oscillating motion to the shaft F, substantially as shown and described.
- 25 3. The combination, with the feed-bar R, supported by the sidewise-sliding plate Q, having the pin Q', of the bell-crank lever P, connected
- 30 by the link O with the lever M', means for imparting a rocking motion to the said lever M' from the oscillating shaft F, and the lever S, operating with its bent arm S' on the pin R', of the feed-bar R, the lever M, connected by
- 35 the link T with the said lever S, and means for imparting a rocking motion to the said lever M from the main oscillating shaft F, substantially as shown and described.
- 40 4. The combination, with the segmental support V, attached to the shaft V', of the frame

W, supporting the said shaft V', and the screw-shaft W², screwing in the said frame W and carrying the hand-wheel W', substantially as shown and described.

5. The segmental support V, mounted on 45 the shaft V', having its bearing on the frame W, in combination with the segmental gear-wheel V², attached to the said shaft V', the worm V³, meshing into the said wheel V², the shaft V⁴, carrying the said worm, and the 50 hand-wheel V⁵, attached to the said shaft V⁴, substantially as shown and described.

6. In a machine for skiving, paring, or thinning leather at the edges, the knife-actuating mechanism consisting of the connecting- 55 rod D, crank E, shaft F, and the crank or arms G and H, in combination with the sliding bar I, carrying the adjustable knife J, substantially as and for the purpose set forth.

7. The feed-bar R, in combination with the 60 shaft F, the links L and L', levers M and M', the links O and T, the levers S and P, and the spring-rods U and U', all effecting a feed-motion of the feed-bar R in such a manner that at each up and down movement of the knife it 65 rises from the leather, passes back laterally, moves down upon the leather and pushes the latter forward, substantially as shown and described.

In testimony whereof we have signed our 70 names to this specification in the presence of two subscribing witnesses.
